UNITED STATES PATENT OFFICE

SIGMUND SCHIFF, OF CINCINNATI, OHIO, ASSIGNOR TO THE J. H. DAY COMPANY, OF CINCINNATI, OHIO, A CORPORATION OF OHIO

EGG WHIP AND THE LIKE

Application filed July 27, 1928. Serial No. 295,830.

This invention relates to whips for beating eggs, cake batter and substances of like consistency and has for an object the provision of a whip which is exceptionally efficient.

5 Another object is to provide a wire cage-type of whip, for the purpose stated, which is free from disadvantages heretofore inherent in this type of device.

Another object is to provide a structure 10 which will permit of the assembly of a greater number of wires than was heretofore practical in devices of this kind.

These and other objects are attained by the means described herein and disclosed in the 15 accompanying drawing, in which:

Fig. 1 represents a composite of two vertical sections taken through the device of the invention, the left-hand side being taken on line A—X as indicated in the several remaining 20 figures; the right-hand side representing a similar view taken on line B—X.

Fig. 2 is an inverted plan view of a member forming a detail of the invention.

Fig. 3 is an inverted plan view of a part 25 forming a detail of the device shown in Fig. 1.

Fig. 4 is an inverted plan view of another part forming a detail of the device in Fig. 1.

The device of the invention comprises a 30 plurality of bent or formed steel wires arranged in a somewhat circular form and having their free opposite ends arranged between plates which are supported on a common shaft. The outstanding advantage of 35 the present structure is its unusual strength

which is due to the manner of retaining the wires with none of the strained or previously formed portions exposed without the retaining means. In the present embodiment 40 there is provided a socket member 8 having a bore 9 for receiving the rotatable shaft of a mixing machine. The body of the socket 8 may have a bayonet slot 10 for mounting the socket on such shaft. The socket is preferably formed with an inverted truncated conical shield 11 which is spread at its lower end 45 to form a plate 12. The flange 11 and plate 12 are connected by a reduced integral neck 13 through which a reduced bore 14 extends 50 in axial alignment with the bore 9.

The plate 12 has an annular concentric row or ring of perforations 15 and a peripheral notch 16 for each of the perforations 16. These are all concentric with the downwardly depending hub 17 of the integral neck 13. 55 A center connecting rod 18 is received in the threaded portion 19 of the bore 14 and serves to threadedly secure to its opposite end the threaded hub 190 of the clamp plate 20. The clamp plate 20 is oval in plan while the plate 12 is larger and circular in plan. The bottom face of the plate 20 (see Fig. 3) has a flat central face 21, an angularly disposed oval face 22 and a shoulder 23 which terminates in a peripheral boss 24. The peripheral boss 24 has a series of grooves 25 extending across it corresponding in number and relative spacing with the perforations 15 and notches 16 in the plate 12. The bottom clamping plate 26 has a flat face for 70 abutment with the flat face 21 of plate 20 and these plates are of substantially similar shape and size so that they are readily mounted one on the other by means of screws 28 extending through coinciding perforations 75 in the plates. The plate 26 is provided with a channel 29 parallel with the periphery of the plate and coinciding with the channel 30 formed adjacent the shoulder 23 in plate 20. As may be best seen in Fig. 4, the bottom of 80 plate 26 has substantially a reversed S-shaped depending vertical vane 31 which has its maximum height at the center and tapers down in each direction to the level of the plate. 85

As may be noted from Figs. 2 and 3, the perforations and notches in the plate 12 and the grooves in the clamp plate 20 are equal in number around the peripheries of those plates and are equally spaced on the individual plates. A number of similar beater wires 32 corresponding to the number of perforations and grooves are provided and are adapted to have their opposite ends secured on the plate 12 and between plates 20 and 26 90 respectively. Each of these wires 32 has at its one end an angularly turned portion or lug 33 made by bending the wire at substantially right-angles to itself and, at its other end a knob or shoulder 34 made by upset- 95

ting, swaging or by other means, the end of the wire. This latter knob is adapted to seat in the channel formed between the coinciding grooves 29 and 30 in the plates and 5 a short portion 35 of the wire lies in a selected one of the grooves 25 in the plate 20. The wires are thus evenly distributed about a periphery of plate 20 and are retained in position by clamping the plate 26 thereover 10 by means of the screws 28.

At the opposite ends of the wires 32, which are given an arcuate form, the lugs 33 are entered into one of the perforations 15 while the body portion 36 adjacent thereto rests 15 in one of the notches 16. An annular clamp plate or ring 37 has perforations 38 disposed about it for receiving screws 39 which enter the threaded bosses 40 in the plate 12 for retaining the ends of the wires 32 in position. 20 The rod 18 has its opposite ends threadedly received in the neck portion 13 and the hub 190 thereby effecting a predetermined spacing of the plates and effecting a predetermined curving of each of the wires 32. The 25 wires or whips 32 being of uniform length and extending from a circular anchorage on the plate 12 are arranged at the opposite end in an oval. The uniform chosen length of the wires is such that at the major diameter of oval plate 20 the lower portion of 30 these wires conform to the inside of the bowl. The resultant cage-like whip is therefore not circular in plan, but is flattened at opposite sides because of the minor diameter A of 35 plates 20 and 26.

With the wires thus retained in position, a very rigid whip is provided. There is no danger of breakage of the wires because those body portions namely 35 and 36 which 40 are retained at the opposite ends are sound and are in no danger of breakage which might occur if force be exerted at the bend of lug 33 or immediately adjacent the shoulder 34. The wires are preferably of non- 45 corrosive metal, for example stainless steel or an equivalent metal and because of their small diameter, may be propelled through a mass of substance to be mixed or beaten with great ease and with a minimum of power. 50 The advantages resulting from the strength, shape and structure of the whips will be apparent in the ensuing description of its operation.

Whips of this type are machine driven, 55 the socket portion 8 being attached to the depending shaft of a mixer in any of the well known ways e. g. by a pin and bayonet slot connection. The substance to be mixed or beaten is placed in a deep mixing bowl and 60 the whip or beater and its actuating shaft (not shown) are lowered until the vane 31 comes in substantial contact with the bottom of the mixing bowl and the major diameter of the cage formed of the wires 32 practically scrapes the side of the bowl. It may

be noted here that the lower half of the maximum curve of the cage or beater, in its preferred form approximates the contour of the lower inside portion of the mixing bowl.

With the substance to be mixed in the bowl and the whip or cage positioned as stated, rotation of the beater will bring certain opposed pairs of the wires 32 into intermittent substantially scraping contact with the inside 70 of the bowl while those spaced 90° from them about the circle will not so closely approach the side of the bowl. The reverse S-shaped vane at the bottom during its rotation continuously throws the lowermost or least agitated portion of the substance outwardly where it will mix with that portion of the substance which is being violently acted upon by the whips. In this way there is no portion of the substance acted upon that is not beaten 80 uniformly with the rest. This is of considerable advantage over previously used wire whips wherein the wires were at their opposite ends secured at the top of the whip and the lowermost portions crossing one another 85 on substantially the axis of the whip. Such a structure obviously limited the number of the wires which might be employed in a given beater because a relatively inactive area equal to the sum of the diameters of the wires, 90 plus clearance, results from the crossing of the wires at the bottom of that old type of whip. Such a mass of crossing merely drags the material with it without effecting a whipping thereof. Numerous means have been 95 resorted to in efforts to improve beaters or whips, some of these including the passing of the individual wires through perforations in the shaft and in various other ways. The present structure however permits of the use 100 of any desired number of wires and each of those wires is active over substantially a uniform 105 area. Furthermore this structure together with the centrifugal vane at the bottom results in a complete uniform 110 and rapid mixing.

As previously explained the wires 32 are of uniform length and are anchored at one end in a circular arrangement while the opposite ends are anchored or retained in an oval. 115 The resultant flattening at opposite sides of the completed whip provides heretofore unattained efficiency and speed for the whip. The whip is turned on its axis and moved bodily through a circumference in the mixing 120 bowl. The axial spinning of the whip provides a momentary substantial contact between the whip (at its major diameter) and the bowl and a succeeding spacing of the whip (at its minor diameter) from the bowl 125 in rapid succession so that a large volume of air is actually drawn into the substance operated on in the bowl by a suction created thereby. This provides a highly desirable, lightness and fluffy consistency of finished 130

product in one half to one fourth the time heretofore required when heretofore used whips were employed.

5 The effective thorough mixing of all of the substance in the bowl has previously been explained. These operating advantages are of value individually as well as collectively. The structural details, one embodiment of which is disclosed herein, provide for simple and inexpensive manufacture.

10 What is claimed is:

1. A beater of the class described comprising a plate having an annular group of perforations therein, a central socket on the plate 15 adapted for attachment to an actuating shaft, a rod depending from said socket portion, a clamp plate secured to the free end of the rod, a co-operating clamp plate adapted for attachment with the first mentioned clamp 20 plate, said co-operating plates having between them an internal channel of substantially elliptical form and a series of spaced transverse grooves communicating with said channel, a plurality of single wires of uniform 25 length having shoulders disposed in said channel, the wires being retained between said co-operating plates, lugs on the opposite ends of the wires for entry into the perforations in the first mentioned plate and an annular 30 clamping member secured to said plate and retaining the wires in position thereon.

2. In a cage-type whip the combination of a socket member comprising a substantially circular plate, said plate having an annular 35 row of perforations therethrough, a plurality of wires, lugs on a given end of said wires for entry into the annularly arranged perforations, a clamp ring secured to the plate and retaining the wires in position, shoulders on 40 the opposite ends of the wires, an axial rod extending from the socket member, a clamp plate mounted on the free end of the axial rod, a co-operating clamp plate adapted to be secured to the first mentioned clamp plate, said 45 clamp plates being channeled and grooved for receiving the shouldered ends of the wires, and a curved vane extending from the exposed face of the outermost clamp plate.

50 3. A whip of the class described comprising a plurality of similar curved wires, a circular plate, means for connecting said plate with an actuating shaft, a clamping means mounted in spaced relation to the first mentioned plate, said plate and clamping means having the opposite ends of the wires secured thereto and a centrifugal vane on the clamp member.

55 4. In combination a circular plate, a pair of oval clamping plates, a plurality of uniform wires attached at their opposite ends to the circular plate and between the oval plates and means to rigidly mount the plates in spaced relation to one another.

60 5. In combination a circular plate, a pair of oval clamping plates, a plurality of uni-

form wires attached at their opposite ends to the circular plate and between the oval plates, means to rigidly mount the plates in spaced relation to one another and a centrifugal vane on one of the oval clamp plates.

6. As a new article of manufacture a beater 70 comprising a multiplicity of uniform wires having their opposite ends terminating in a pair of spaced planes, the ends of the wires at one end of the beater lying in a circle and at the other end lying in an ellipse.

7. As a new article of manufacture a beater 75 comprising a multiplicity of spaced curved wires of uniform length, the wires forming a substantially globular cage having intersecting transverse diameters of unequal length.

8. As a new article of manufacture a whip 80 comprising spaced wires arranged to form a globular cage having a pair of opposed flattened sides.

9. As a new article of manufacture a globular wire cage type whip adapted for rotation about its axis and being of oval cross section in a plane intersecting said axis of rotation at right angles.

10. A cage type rotary whip comprising a plurality of wires of uniform length a pair of members receiving between them an end of each of the wires and clamping the wires in spaced relation, a second pair of members receiving the remaining end of each wire between them and clamping them in spaced relation, and means rigidly connecting the pairs of members in spaced relation for developing the plurality of wires into a substantially globular flat-sided body with each wire positioned in a simple arcuate curve.

11. As a new article of manufacture a whip 95 comprising spaced wires arranged to form a globular cage having a pair of opposed flattened sides, and a centrifugal vane disposed at one end of said cage.

In testimony whereof, I have hereunto subscribed my name this 23rd day of July, 1928.
